Primary Examiner — Richard Edgar*Assistant Examiner* — Jessica Ruth Grable(74) *Attorney, Agent, or Firm* — Cooper Legal Group, LLC(57) **CLAIM**

The ornamental design for a crib frame as shown and described.

DESCRIPTION

FIG. 1 is a front elevational view of a crib frame showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a third perspective view thereof; and,

FIG. 10 is an enlarged view of the encircled portion '10' in FIG. 1 thereof.

The broken lines shown in FIGS. 1-10 are included for the purpose of illustrating portions of the crib frame that form no part of the claimed design.

The long dash-short dash broken lines shown in FIGS. 1 and 10 illustrate boundaries of enlargement that form no part of the claimed design.

1 Claim, 10 Drawing Sheets10
